UNITED STATES PATENT OFFICE.

ANTHONY ELTON DAVIS, OF PHILADELPHIA, PENNSYLVANIA, ASSIGNOR OF ONE-HALF TO FREDERICK J. GEIGER, OF PHILADELPHIA, PENNSYLVANIA.

VAULT-LIGHT, FLOOR-LIGHT, PAVEMENT-LIGHT, OR SKYLIGHT CONSTRUCTION.

1,241,825.

Specification of Letters Patent.

Patented Oct. 2, 1917.

Application filed May 15, 1912. Serial No. 697,381.

To all whom it may concern:

Be it known that I, ANTHONY ELTON DAVIS, a citizen of the United States, residing in the city and county of Philadelphia, 5 State of Pennsylvania, have invented a new and useful Vault-Light, Floor-Light, Pavement-Light, or Skylight Construction, of which the following is a specification.

My present invention relates to a vault light, floor light, pavement light or skylight construction in which a plurality of reinforced concrete beams or lintels are employed which form the support for the lenses or tiles and which are preferably provided 10 with bonding elements in order to interlock with a second layer of binding material such as concrete for example, which surrounds the lenses and is anchored to the beams or lintels in such a manner that the 15 expansion and contraction of the concrete construction will be substantially uniform throughout its mass.

With the above and other objects in view which will hereinafter more clearly appear 20 in the detailed description, my invention consists of a novel vault light, floor light, pavement light or sky light construction which may be very economically manufactured and assembled and which may be 25 completed at the place of installation by unskilled labor with consequent decrease in the cost of production.

It further consists of a novel construction 30 of a vault light, floor light, pavement light or sky light construction comprising a plurality of reinforced concrete beams or lintels which are spaced apart in order to form 35 openings adapted to be covered by the lenses or tiles and such beams or lintels may be 40 spaced apart in a variety of ways, and if desired, they may be provided with arms integral therewith or secured thereto, and such arms may interlock with the beams or 45 lintels or be secured thereto in any desired manner.

My invention further consists of a novel 50 vault light, floor light, pavement light or sky light construction in which reinforced beams or lintels are provided on their upper faces with anchoring or bonding elements, and with laterally extending spacing members which form openings adapted 55 to be covered by the lenses or tiles, and after the lenses or tiles are placed in position, a layer of concrete is formed which surrounds

the lenses and interlocks with the bonding or anchoring elements, whereby the layer of concrete formed *in situ* is bonded with the preformed beams or lintels.

It further consists of other novel features of construction, all as will be herein-after fully set forth.

For the purpose of illustrating my invention, I have shown in the accompanying drawings, preferred embodiments thereof which are at present preferred by me, since the same have been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a vault light, floor light, pavement light or sky light construction embodying my invention.

Fig. 2 represents a sectional elevation of 80 a portion of Fig. 1.

Fig. 3 represents a perspective view of another embodiment of my novel vault light, floor light, pavement light or sky light construction.

Fig. 4 represents a perspective view of 85 one type of beam or lintel which may be advantageously employed.

Figs. 5, 6, 7, 8 and 9 represent, respectively, perspective views of other embodiments of my invention.

Similar numerals of reference indicate corresponding parts in the figures.

Referring to the drawings:

The reinforced concrete beams or lintels 90 1 are preferably preformed and consist of reinforcements 2 of any desired nature, embedded in concrete and it is to be understood that the contour of the beams may vary widely in practice.

The upper face of the beams or lintels 95 may have any desired conformation but are preferably flat and are provided with bonding or anchoring elements 3 of any desired nature and in the different embodiments of 100 my invention I have shown different types which may be employed, it being understood that I do not desire to be limited to any special type or conformation of bonding or anchoring elements.

- In the embodiment seen in Fig. 1 the beam or lintel is provided with laterally extending arms 4, the ends of which are adapted to abut against the adjacent beam 5 or lintel thereby forming an aperture 5 which is covered by a lens or tile 6, the contour and type of which will vary in accordance with the conditions met with in practice and with the shape of the opening 5.
- After the lenses 6 are placed in position a layer of concrete or other binding material 7 is placed on the beams 1 and the spacing arms 4 to interlock with the bonding or anchoring elements 3 and surround the lenses 6 preferably flush with the upper face thereof. In the present instance, the lenses 6 employed are provided with ribs or beads 8 in order that a better interlocking of the lenses with the layer 7 of concrete formed *in situ* will be produced. The layer of concrete 7 is bonded to the preformed beams or lintels by means of the anchoring elements 3 so that a reinforced concrete construction is attained.
- In the embodiment seen in Fig. 3 instead of having the spacing bars integral with the beams or lintels I employ a reinforced concrete lintel 9 having recesses 10 in its upper faces with which the reduced neck 11 of spacing bars 12 interlock, said spacing bars and lintels forming openings 13 to be covered by lenses in the same manner as the embodiment seen in Fig. 1, it being noted that bonding elements 14 of any desired type are carried by the lintels 9.
- In the embodiment seen in Fig. 5, the construction is similar to Fig. 1 except that strips 15 are employed secured to the lintels by pins 16 which, if desired, project upwardly to form bonding elements.
- In the embodiment seen in Fig. 6, a different manner of securing together the lintels is shown, a reinforced concrete lintel 17 having a spacing arm integral therewith, the end of which forms a dovetail joint as at 18, with the adjacent lintel. A different construction of bonding element is shown in Fig. 6.
- In the embodiment seen in Fig. 7, the spacing arms 19 have a lip 20 interlocking with a recess 21 in the adjacent lintel, a different type of bonding element being shown.
- In the embodiment seen in Fig. 8 a reinforced concrete lintel 22 has rectangular shaped recesses 23 on opposite sides thereof adapted to receive short spacing bars 24, and a different type of bonding element is shown.
- In the embodiment seen in Fig. 9, 26 designates a reinforced concrete lintel having straight spacing arms 27, the ends of which seat in correspondingly shaped recesses 28 in an adjacent lintel and are secured thereto by fastening devices 29. The bonding

elements 30 are shown as consisting of concrete projections of greater dimensions at their outer end than they are at their inner ends.

It will now be clearly apparent that in all the embodiments of my invention herein illustrated a reinforced concrete lintel having any desired contour is formed which when installed is spaced from an adjacent lintel in such a manner as to form openings adapted to be covered with lenses or tiles, and after such lenses or tiles are placed in position, they are surrounded with concrete or other binding material which also embeds the bonding elements in case they are employed.

It is immaterial in the broad scope of my invention whether or not the lintels are spaced from each other by spacing members integral therewith or separate therefrom. It is also immaterial whether or not the spacing arms are in contact with interlock with or are secured to an adjacent lintel.

Any desired type of bonding or anchoring elements may be employed. In my novel construction the expansion and contraction of the concrete does not place undue strain on the glass and thereby eliminates in a large measure the breaking of the lenses or tiles.

I prefer in practice to preform the lintels, but if desired they may be made at the place of installation.

It will now be apparent that I have devised a novel and useful construction of a vault light, floor light, pavement light or sky light construction which embodies the features of advantage enumerated as desirable in the statement of the invention and the above description, and while I have, in the present instance, shown and described preferred embodiments thereof which have been found in practice to give satisfactory and reliable results, it is to be understood that the same are susceptible of modification in various particulars without departing from the spirit or scope of the invention or sacrificing any of its advantages.

Having thus described my invention, what I claim as new and desire to secure by Letters Patent, is:—

1. In a vault light, floor light, or sky light construction, a plurality of lintels each comprising a reinforced concrete element adapted to span the opening to be covered and having transverse members to space each element from an adjacent element to form therewith lens receiving openings.

2. As a new article of manufacture, a reinforced concrete lintel having angularly disposed arms to form with a corresponding lintel, lens receiving openings, and the upper face of the lintel being provided with exposed bonding elements.

3. In a vault light, floor light, or sky light

construction, a plurality of lintels each comprising a reinforced concrete element adapted to span the opening to be covered and having transverse members interlocking with and spacing each element from an adjacent element to form therewith lens receiving openings.

4. As a new article of manufacture, a reinforced concrete lintel having angularly disposed arms formed to interlock with an adjacent lintel and form therewith lens receiving openings, and the upper face of a lintel having bonding elements thereon.

5. In a vault light, floor light, pavement light or sky light construction, reinforced concrete lintels having angularly extending arms forming with an adjacent lintel lens receiving openings, lenses covering said openings, and a layer of concrete surrounding said lenses.

6. In a vault light, floor light, pavement light or sky light construction, reinforced concrete lintels having angularly extending arms forming with an adjacent lintel lens receiving openings, means for securing said lintels in spaced position, lenses covering said openings, and a layer of concrete surrounding said lenses.

7. In a vault light, floor light, pavement light or sky light construction, reinforced concrete lintels having angularly extending arms forming with an adjacent lintel lens receiving openings, bonding elements carried

by and extending above the upper face of said lintels, lenses covering said openings, and a layer of concrete surrounding said lenses and embedding said bonding elements.

8. In a vault light, floor light, pavement light or sky light construction, a plurality of independent and preformed reinforced concrete lintels, means to space said lintels apart and operatively connect them to form lens receiving openings, and lenses secured over said openings.

9. In a vault light, floor light, pavement light or sky light construction, a plurality of independent and preformed reinforced concrete lintels, means to space them apart and operatively connect them to form lens receiving openings, lenses covering said openings, and a layer of binding material surrounding said lenses.

10. In a vault light, floor light, pavement light or sky light construction, a plurality of independent and performed reinforced concrete lintels, means to space them apart and operatively connect them to form lens receiving openings, bonding elements carried by and extending above said lintels, lenses covering said openings, and a layer of binding material embedding said bonding elements and surrounding said lenses.

ANTHONY ELTON DAVIS.
